Primary Examiner — Susan M Lee(74) *Attorney, Agent, or Firm* — Cantor Colburn LLP(57) **CLAIM**

The ornamental design for a data scan device, as shown and described.

DESCRIPTION

FIG. 1 is a perspective view of a data scan device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof;

FIG. 9 is a reference view thereof when in use; and,

FIG. 10 is another reference view thereof when in use.

Broken lines and unshaded portions contained within broken lines are not claimed.

1 Claim, 8 Drawing Sheets(56)
